UNITED STATES PATENT OFFICE.

OWEN A. KENEFICK, OF LAWRENCE, MASSACHUSETTS.

DISPLAY STAND.

Application filed October 21, 1922. Serial No. 596,100.

To all whom it may concern:

Be it known that I, OWEN A. KENEFICK, a citizen of the United States, residing at Lawrence, in the county of Essex and State 5 of Massachusetts, have invented certain new and useful Improvements in Display Stands, of which the following is a specification.

This invention relates to display cabinets and is especially designed for use in the 10 rooms of lodges and other societies which wish to keep a roll of honor or roll of deceased members, particularly of those who have deceased recently.

It comprises in general a pedestal or 15 stand on which is mounted a cabinet with an opening in the front. Over this opening in the front is an illuminated transparent sign, and under or behind it are other illuminated signs, while directly behind is a 20 record holder which may be of any permanent form or, preferably, provided with removable records.

Preferably also, under the cabinet and 25 over the pedestal, is a drawer or container in which to store the old records and unused records.

In the drawings, Fig. 1 is a front elevation of my cabinet and pedestal.

Fig. 2 is a side elevation as from the left 30 of Fig. 1 with parts of the cabinet broken away to show the interior.

Fig. 3 is a front elevation of the record holder removed from the cabinet.

In the drawings, A is a pedestal which 35 rests upon the floor, such as T, or a table, platform, or other suitable resting place.

On top of the pedestal A, I show a base B provided with an opening for a drawer 40 11 of suitable size to contain the old and unused records or cards 12 which fit into the record holder H. Preferably, this container B is provided with doors 10 which are ornamental on the outside and whereby the opening for the drawer 11 can be closed.

F is a cabinet, preferably, of ornamental 45 form, in the front of which is an opening G. Over this opening G, I provide a transparent sign 20 and at the bottom other glass signs 21, each containing any suitable 50 legend.

The record holder H is shown as in the 55 form of an imitation book into which can be inserted from time to time the blank record cards upon which names and other inscriptions can be placed until the card is filled.

After being filled, it can be removed and placed in the drawer 11 and a new card substituted.

I prefer to illuminate the inside of my 60 cabinet, together with the signs 20 and 21 and the record holder H, by means of electric bulbs, the current for which may be supplied by means of a cable such as C.

As shown, one or more bulbs 40 are located 65 near the top of the cabinet behind the sign 20 in position to illuminate the front of record holder H, and one or more other bulbs 41 are located at the bottom of the cabinet behind the signs 21.

I find it convenient to cover the bulbs 41 70 with a case 42 having a shoulder 43 upon which the record holder H can rest, the other or top end resting against the back 15 of cabinet F. This back may be attached by hinges 16 and the record holder H passed 75 in from the back, or the opening G may be of such size that it can be passed in from the front.

As shown, this record holder includes a 80 rectangular wooden frame 50 with a glass front 51 behind which is a sheet metal or pasteboard support 52 ornamented to imitate a book and having rectangular openings 56 and 57.

Behind these openings 56 and 57, the 85 cards 12 are placed and are held in position by a back 53 which may be held in position by buttons such as 54, or by any other convenient means.

The case 42 may have a back door 44 hinged at the bottom and with a catch at the top, or may be open at the back.

It is obvious that the pedestal may be dispensed with and the cabinet may rest upon 90 a table or other support, as indicated by line x—y of Fig. 1.

It is also obvious that the opening, such 95 as G, may be fitted with transparent glass such as indicated by the dotted lines 27 100 shown in Fig. 2.

I claim:

1. In a display device, the combination 105 with a cabinet having an ornamental front with an opening, a transparent sign above the opening, and a box with a shoulder at the back and a transparent sign at the front behind the bottom of said opening; of a bodily removable record holder of ornamental form positioned in the cabinet at a slant 110 behind said opening and resting on said shoulder and against the back and having

openings for the insertion of different records; an electric light at the top of the cabinet positioned to illuminate the sign and also the record holder; and another 5 electric light in said box.

2. In a display device, the combination with a cabinet having an ornamental front with an opening, a transparent sign above the opening, and a box with a shoulder at the 10 back, behind the bottom of said opening; of

a bodily removable record holder of ornamental form positioned in the cabinet at a slant behind said opening and resting on said shoulder and against the back and having openings for the insertion of different 15 records; an electric light at the top of the cabinet positioned to illuminate the sign and also the record holder.

OWEN A. KENEFICK.
